UNITED STATES PATENT OFFICE.

CARL O. JOHNSON, OF LINCOLN, NEBRASKA, ASSIGNOR TO HIGHWAY MAINTAINER COMPANY, OF HAVELOCK, NEBRASKA, A CORPORATION OF NEBRASKA.

SURFACE MAINTAINER

Application filed October 19, 1925. Serial No. 63,337.

My invention relates to implements of the kind which are adapted for the purpose of maintaining the surface of a road in good condition as distinguished from those implements whose function is to build the road.

The drags which are commonly used for a somewhat similar purpose have an exceedingly limited range of usefulness. They are heavy of weight and awkward in use; they are short-lived, and they can perform their function only when the soil is in proper condition. They can operate only over narrow strips of the roadway at a time. Both the cost of the drag with its depreciation and upkeep and the labor cost of operating the drag are excessive. Briefly then, the object of my invention is the provision of a surface maintainer which will do all of the work which the drag is capable of doing, which will work the road over one-half or less of the width at one time, which will do the work much more effectively and which may be operated at lower implement and labor costs than the corresponding costs of operating drags. Having in view these objects and others which will be mentioned in the following description, I will now refer to the drawings, in which—

Figure 1 is a plan view of the scrapers and scraper frame.

Figure 2 is a sectional view of the scraper blade showing the relation to the frame.

Figure 3 is a perspective view of the gate.

Figure 4 is a view in perspective of the mechanism for adjusting the front portion of the scraper frame and showing also the link device for locking the scraper frame to the vehicle frame.

Figure 5 is a perspective view of the means for adjusting the rear portion of the scraper frame.

Figure 6 is a view in perspective of the entire implement.

It should be borne in mind that this implement is designed for maintaining the surface of a highway in good condition. For this purpose I employ a vehicle frame and a scraper frame, only fragmentary portions of the vehicle being shown. The blades which I use in the scraper frame are shown in section in Figure 2, the blade 10 being secured to the angle iron 11 of the frame and being reversible in position thereon. By this means when one edge of the blade becomes worn down to its angle iron support, the

bolts may be removed and the blades reversed, which doubles the life of the blades and does away with the necessity of carrying a supply of new blades. The scraper frame comprises four transverse angle irons 12, 13, 14, and 15 which are secured at various points to the angle irons of the respective scraping blades. The angle irons 12 and 13 are braced by the diagonal braces 16 and 17 which are secured together at their intersections and they are further braced by means of the draw bars 18 and 19. The angle irons 13 and 14 are connected by the diverging braces 16' and 17'. The angle irons 12 and 13 are the longest of the angle irons and the initial and heaviest strain is applied to them, but the system of bracing prevents any buckling or other weakening of these two angle irons. At the sides of the scraper frames are two scrapers 20 and 21 extending rearwardly and inwardly at equal angles to the line of draft, the blade 20 being a little longer than the blade 21. At the right hand side of the implement is a blade 22 which terminates short of the median line of the implement and at the left hand side is a similar but longer blade 23 extending almost to the blade 21. Both of these blades are secured to the angle irons 12 and 13, and the blade 23 is additionally secured to the angle iron 14. In addition the blade 22 is braced by means of the brace 24 extending to the angle iron 14, and the blade 23 is braced by means of the braces 25 and 26 to the angle irons 14 and 15 respectively.

The angle iron 30 is projected rearwardly from the upper edge of the blade 20 and is secured to the angle iron beam of the blade 20. It functions as a brace for the blade 27 and as a support for the gate 29. An additional brace 28 connects the blade 27 to the angle iron 15. The rearward extension of the angle iron of the blade 20 has a more important function, however, in supporting the gate 29 shown in Figure 3. This gate 29 is made of material similar to that of which the blades are made and it has the same dimensions so that when it is in closed position it may serve as an extension of the scraper blade 20. The angle iron 30 is secured above the blade 20 as shown in Figure 3, and it has secured thereto two L-shaped pieces of strap iron 31. The gate 29 has a short length of angle 110

iron 32 bolted thereto, and projecting upwardly from the angle iron are ears 33 formed on the L-shaped pieces of strap iron which are secured to the angle iron 32. The ears 31 and 33 are so spaced that they may be pivotally secured to each other by means of the rod 34. Also secured to the angle iron 32 is a goose neck lever 35 which has a rod 36 secured thereto. As shown in Figure 1 this rod extends over the brace 28 and it may be locked in any desired position or left loose so that the gate may float. Any desired form of locking device may be employed for releasably locking the rod 36 to the brace 28.

The scraper frame is positioned underneath the vehicle frame and is suspended therefrom. The front portion is provided with two eyes 37 for securing it to the links 38, one of which is shown in Figure 4. The link 38 is pivotally connected in end to end relation with the link 39, and the link 40 is pivotally secured to the link 38 near its lower extremity. The link 41 is pivotally secured to the link 40 at its upper extremity and the links 39 and 41 are each pivotally secured to the arm 42 of the rack 43. This rack is secured between two standards 44 on the vehicle frame. The rack 43 is actuated through the screw 45 which is secured to the shaft 46 having the hand wheel 47 also secured thereto. The weight of the scraper frame, however, is such that the screw and rack will not hold the scraper in adjusted position, and in order to prevent the downward movement of the scraper frame there is provided a pivoted brake 48 which is held in contact with the hand wheel 47 by the tension spring 49, the brake being releasable by means of the pivoted foot lever 50. The scraper frame is permitted to float by the fact that the links 39 and 41 and the links 38 and 40 will spread and come together as the scraper frame rises and falls. These links must, however, never be permitted to get into alignment with each other as this would lock them into fixed position so that it would be necessary to leave the machine at frequent intervals to unlock them manually. To prevent the accidental locking of the levers into alignment, the links 39 and 41 are each bent inwardly as shown in Figure 4, the bent ends limiting the inward movement of the links by the bent ends coming into contact with each other. In the working in the surface of the road it is, however, sometimes necessary that the front portion of the scraper frame be held locked in fixed position. The latch lever 51 is pivotally secured to the pivot pin connecting the links 38 and 39 and it is notched to engage the projecting pivot pin connecting the links 40 and 41.

The scraper frame is further connected to the vehicle frame through the chains 52,

53, and 54. The chains 52 and 53 are crossed chains which are secured at their respective ends to the scraper frame and to the vehicle frame but on opposite sides thereof. The chain 54 is connected at its ends 70 to the opposite sides of the scraper frame and it is provided with a grab link 55 which is shown in Figures 1 and 5. On the vehicle frame is a pulley 56, and the grab link 55 is connected with the chain 57 passing over the pulley 56 and is secured to the shaft 58 having a hand wheel 59. The turning of the hand wheel 59 thus raises or lowers the rear portion of the scraper frame. The pulley 56 is adjustable in position transverse of the vehicle frame and the grab link 55 is slidable on the chain 54, thus providing for considerable lateral adjustment of the scraper frame when manipulating the hand wheel 59.

When transporting the implement to the road which is to be worked, the implement frame is held in raised position above the surface of the ground. The wheeled vehicle which supports the implement frame is drawn by a tractor. For working the road the implement frame is lowered through the hand wheels 47 and 59 until the scrapers rest on the surface of the road. The draw bars 18 and 19, having goose necks in the connections between the scraper frame and the vehicle frame, cause a downward thrust on the forward portion of the scraper frame. The forward portion of the scraper frame is heavier than the rear portion and this, combined with the downward thrust through the goose neck levers, results in the heaviest work being done by the scrapers at the front portion of the implement. The scrapers 20 and 23 tend to drag on the left hand side 105 of the implement, while the scrapers 21, 22, and 27 cause a drag on the opposite side of the implement which counterbalances the drag on the scrapers 20 and 23 so that there is no side draft. All of the scrapers are inclined with respect to the line of draft, the result being that they cut with a sliding action. In passing over the road the scrapers 22 and 23 cut down hummocks in the road and transport the soil along their edges. The soil which is transported by the scraper 22 falls against the scraper 23 at substantially the center line of draft where it meets the soil moved by the scraper 23. The scraper 22 moves over the ruts on the right hand side of the road but since its primary function is to cut down the protuberances in the road, it will deposit very little soil in the ruts. The soil carried by the scraper 23 also passes over the ruts on the left hand side of the road, but this soil is deposited in or near the ruts on the right hand side. The soil which is loosened by the scrapers 20 and 21 is carried toward the center or rather to the ruts on both sides. The further forward 110

115

120

125

130

movement of the implement causes all this accumulated soil to be engaged by the scraper 27 which drags the mass of soil over the ruts on both sides of the road. The soil is thus rolled into the cavities and all of the other depressions in the road, and the soil in the depressions is compacted first by the rolling and then by the weight of the rear portion of the implement when the scraper 27

10 passes over the depressions.

During the operation of the implement as above described, the gate 29 is kept in its closed position so that it forms a continuation of the scraper 20. It sometimes happens, however, that accumulation of soil in the rear portion of the scraper frame becomes too great. If the gate is then opened the excess of soil may be discharged through the gate where it slides along the scraper 27

20 to the center or side of the road. When working stony soil, it is desirable that the gate be left in open position so as to discharge the larger stones and rocks. At other times it may be desired to permit the gate to

25 float. This affords a slight pressure against the soil in storage, but when the mass becomes too great, the pressure of the soil will open the gate to discharge the surplus.

The greatest pressure of the soil is at the 30 intersection of the blade 27 with the support for the blade 20. This induces a slight tilt in the implement frame, causing the implement to raise slightly at the point of intersection of the blades 21 and 27. To overcome this difficulty the grab link 55 may be adjusted on the chain 54 toward the blade 20 and the hand wheel 59 may be turned so as to lift the left hand rear corner of the implement very slightly to thus throw the pre- 35 ponderance of weight on the right hand rear corner. The pulley 56 is also adjustable toward the left so that it is possible to obtain considerable inequalities of lift on the right and left hand rear corners. When soil is dis- 40 charged at the right hand rear corner it leaves a slight trail on the road but when it is discharged from the left hand rear corner it moves along the blade 27 to the middle or edge of the road.

50 Having thus described my invention in such full, clear, and exact terms that its construction and operation will be readily understood by others skilled in the art to which it pertains, what I claim as new and desire 55 to secure by Letters Patent of the United States is:—

1. A surface maintainer comprising a wheeled frame and an implement frame suspended therefrom, said implement frame including a pair of lateral rearwardly converging scrapers of unequal lengths, a rearwardly and inwardly inclined scraper secured at the forward extremity of one of said pair of scrapers and terminating substantially at

frame, a rearwardly and inwardly inclined scraper secured at the forward extremity of the other of said pair of scrapers, said last named scraper being longer than said first named rearwardly and inwardly inclined 70 scraper, and a scraper secured at the rear extremities of said pair of rearwardly converging scrapers and projecting outwardly beyond the longer of said pair of rearwardly converging scrapers. 75

2. A surface maintainer comprising a wheeled supporting frame and an implement frame suspended therefrom, said implement frame including a front frame member, a pair of lateral rearwardly converging members of unequal lengths, and a rearwardly and laterally inclined member connecting the rear end portions of said pair of converging members and projecting outwardly beyond the longer of said pair of converging members; said rearwardly and laterally inclined member and said pair of converging members each having secured thereto a scraping blade, the scraping blade for the longer of said pair of converging members being of such length that an opening is provided between its rear extremity and the scraping blade of said rearwardly and laterally inclined member, and means for closing the opening. 95

3. A surface maintainer comprising a wheeled supporting frame and an implement frame suspended therefrom, said implement including a pair of lateral rearwardly converging scraper blades of substantially equal lengths, a rearwardly and laterally inclined scraper blade secured to one of said pair of converging blades and providing an opening between it and the other of said pair of converging blades, and a gate for closing the opening to provide for the storage of soil between said converging blades and said rearwardly and laterally inclined blades, and manually operable means for actuating said gate to opening and closing positions. 100

4. A surface maintainer comprising a wheeled supporting frame and an implement frame suspended therefrom, said implement frame including a pair of lateral inwardly converging angle iron members and a rearwardly and laterally extending angle iron member connecting said pair of converging angle iron members at their rear extremities, scraping blades secured to each of said rearwardly and laterally extending angle iron member and said pair of converging angle iron members, one of the converging pair of said blades being provided with an opening at its rear extremity, a gate which is adapted to close the opening, said gate being pivotally secured at its upper edge to the angle iron and being movable to opening and closing positions, and a manually operable latch for latching said gate in

115 its closing position or in any of its opening 120 125 130

positions, said latch when in its inoperative position permitting said gate to yield under the pressure of the accumulated soil.

5. A surface maintainer including a wheeled frame and an implement frame suspended therefrom, said implement frame having secured thereto a pair of lateral rearwardly converging scraper blades and a transverse rearwardly and laterally projecting scraper blade, adjustable connections between said wheeled supporting frame and said implement frame for raising and lowering said implement frame, said connections including links at the forward portions of 10 said frame, said links being pivotally connected in quadrilateral form to permit the floating of said implement frame, means for locking said links together against pivotal movement, said connections including also 15 a rear transverse chain on said implement frame, a chain and a windlass therefor on

said wheeled frame, and a grab link connection between said two chains whereby the rear portion of said implement frame may be tilted by adjusting said two chains and 25 operating said windlass.

6. A surface scraping implement including rearwardly converging beams having scraper blades secured thereto, a rear barrier connecting said beams at their rear extremities and projecting laterally beyond one of said beams, the scraper blade on the side of the projecting extremity of said barrier terminating short of said barrier to provide an opening between said barrier and 30 the blade whereby the scraped material is carried along said barrier during the forward travel of said implement and deposited to one side of the center line of travel thereof, and a closure for the opening. 35

In witness whereof, I affix my signature.
CARL O. JOHNSON. 40
